UNITED STATES PATENT OFFICE.

WILLIAM J. HAGMAN, OF PHILADELPHIA, PENNSYLVANIA, ASSIGNOR TO NILES-BEMENT-POND COMPANY, OF NEW YORK, N. Y., A CORPORATION OF NEW JERSEY.

PLANER AND ATTACHMENT THEREFOR.

1,296,795.

Specification of Letters Patent. Patented Mar. 11, 1919.

Application filed June 13, 1917. Serial No. 174,517.

To all whom it may concern:

Be it known that I, WILLIAM J. HAGMAN, a citizen of the United States, residing at Philadelphia, in the county of Philadelphia and State of Pennsylvania, have invented certain new and useful Improvements in Planers and Attachments Therefor, of which the following is a specification.

It is frequently desired to use a planer to plane surfaces which are in deep recesses. To do this work it has heretofore been necessary either to provide an excessively long tool or to provide a special tool slide adapted to project into the recess. Each of these methods is of limited utility and each of them is open to the serious objection that it subjects the tool heads and the cross rail to abnormal turning or twisting stresses for which they were not intended.

The principal object of the invention is to provide a planer or an attachment therefor which is adapted for planing surfaces which are located in deep recesses. In accordance with my invention, planing can be effected in very deep recesses and can be done without subjecting the tool heads and cross rail to any undue or abnormal stresses.

In the accompanying drawings I have shown one embodiment of the invention, but it will be understood that the drawings are for illustrative purposes only and are not intended to define or limit the scope of the invention, the accompanying claims being relied upon for that purpose.

Of the drawings:

Figure 1 is a side view of a planer embodying the invention.

Fig. 2 is a front view.

Fig. 3 is a partial plan view.

Fig. 4 is a detail view showing the means for holding the tool bar.

Fig. 5 is a detail view showing the lower end of the tool bar.

Fig. 6 is a detail view showing the devices for connecting the tool with the tool bar.

In the drawings I have illustrated somewhat fully many of the principal elements of a planer, but it will be understood that

most of these elements are well known and do not by themselves constitute any part of this invention.

As illustrated, the planer comprises a bed 1 upon which is mounted a reciprocating table 2. The table is driven in any usual or preferred manner, as, for instance, by means of the belt pulleys 3 and 4 which are connected with the table through any suitable gearing. For reversing the movement of the table there is provided a belt shifter 5 which is operated by dogs 6 and 7 carried by the table. At the sides of the bed are suitable uprights or housings 8 and 9 which are connected by an arch 10. Vertically adjustable along suitable ways on the uprights 60 is a cross rail 11. This rail can be moved vertically by means of screws 12, 12 which are suitably connected to receive power from a belt wheel 13.

Mounted on the cross rail 11 are one or more tool heads, and in the drawings two tool heads are illustrated. Each tool head comprises a saddle 15 which is horizontally movable along ways formed on the cross rail. Angularly adjustable on the saddle is 70 a swivel plate 16 and adjustable along ways formed on the swivel plate is a slide 17 adapted to be controlled by a screw 18. Angularly adjustable on the slide 17 is a plate 19 adapted to be secured in adjusted 80 position by means of bolts 20, and horizontally pivoted to the plate 19 is an apron 21 adapted to carry the cutting tool.

For moving either or both of the tool heads horizontally along the rail in either 85 direction, there are provided two horizontally threaded shafts 22 and 23. For moving either or both of the slides 17 vertically or angularly in either direction, there is provided a horizontal shaft 24 which is 90 provided with a keyway throughout, and which is adapted to turn the screw 18 by means of suitable gearing not shown. The construction is such that the power connection with the screw 18 is maintained for all 95 angular positions of the slide and swivel plate. For turning any or all of the said shafts 22, 23 and 24, there is provided a

suitable feed mechanism 25 which is illustrated in part in Figs. 1 and 2 and which receives its power from the main drive mechanism. This feed mechanism need not 5 be described in detail, and it will be sufficient to point out that it serves upon each movement of the table 2 to turn one or more of the said horizontal shafts through a definite angle to effect the required movement 10 of the tools.

Referring now to those parts of the construction to which my invention more particularly relates, 26 represents a tool-carrying bar which is adapted to be connected to 15 the apron 21 in place of the usual tool. Preferably, in order that the bar may be securely connected to the apron, I provide a special clip 27 for holding it, this clip being adapted to be held by bolts 28 which enter 20 the usual T-slots with which the apron is provided. By means of the clip the bar is held in an upright position but can be adjusted angularly in accordance with the angular adjustment of the slide 17 and 25 plate 19.

At the lower end of the bar 26, means are provided for holding a cutting tool. As illustrated, there is a plate 29 which is provided with a pivot boss 30 which extends 30 through an aperture in the bar. The boss is threaded at its rear end to receive a nut 31 which, when tightened, clamps the plate 29 in position. Horizontally pivoted to the plate 29 is an apron 32 which carries bolts 35 and clips whereby the cutting tool 33 is secured.

Extending across the planer from one housing to the other is a supplemental rail 34 which is positioned to contact with the 40 front face of the bar 26. This rail is positioned at a relatively high elevation and is held in place by any suitable means such as the brackets 35, 35 which are connected with the uprights.

45 As clearly shown in Fig. 2, the bar 26 permits the cutting tool 33 to be positioned in a recess at a point which could not be reached by a planer as ordinarily constructed. The pivotal mounting of the plate 29 permits the 50 tool to be turned to one side or the other as required, and the pivoting of the apron 32 permits the tool to be relieved during the backward movement of the work. The bar 26 can be adjusted in any of the ways in 55 which the cutting tool is usually adjusted. That is, the bar can be moved upward or downward in the clip 27 and can be secured in adjusted position; angular adjustment can be effected by means of the plate 19 or 60 the swivel plate 16; and the bar can be moved vertically or angularly or horizontally either preliminarily or during operation by means of the feed mechanism.

The cross rail 34 serves to support the bar 65 26 and prevents the reaction resulting from

the cutting from being transmitted to the cross rail in the form of a twisting stress thereon. The rail 34, while fully supporting the bar in the way described, nevertheless leaves it free to be adjusted either vertically 70 or horizontally or angularly as required.

What I claim is:

1. An attachment for a planer, comprising a long tool-carrying bar adapted to be secured to a tool head, and means adapted to be secured to the planer uprights independently of the cross rail, the said means engaging the bar at a place remote from the tool head and thus relieving the tool head 75 from excess stress.

2. An attachment for a planer, comprising a long tool-carrying bar adapted to be secured to a tool head, and a supplemental rail adapted to be secured to the planer uprights independently of the cross rail, the said rail 80 engaging the bar at a place remote from the tool head and thus relieving the tool head from excess stress.

3. An attachment for a planer, comprising a bar adapted to be secured to a tool head in upright position, means for connecting a tool with the bar at its lower end, and a supplemental rail adapted to be secured to the planer above the tool head and independently of the cross rail, the said rail 90 engaging the bar near its upper end and thus relieving the tool head from excess stress resulting from cutting pressure on the tool.

4. An attachment for a planer, comprising a tool-carrying bar adapted to be secured 100 to a tool head, and a supplemental rail adapted to be secured to the planer, uprights independently of the cross rail above and parallel to the said cross rail, the said supplemental rail engaging the front face 105 of the bar near the upper end thereof and thus serving to relieve the tool head from excess stress.

5. The combination in a planer, of a reciprocating table, uprights at the sides of 110 the table, a cross rail carried by the uprights, a tool head on the cross rail, a long bar secured to the tool head and adapted to carry a cutting tool at its lower end, and means mounted on the uprights independently of 115 the cross rail and engaging the bar near its upper end to relieve the tool head from excess stress.

6. The combination in a planer, of a reciprocating table, uprights at the sides of 120 the table, a cross rail carried by the uprights, a tool head on the cross rail, a long bar secured to the tool head and adapted to carry a cutting tool at its lower end, and a supplemental transverse rail mounted on the 125 uprights independently of the cross rail and engaging the bar near its upper end to relieve the tool head from excess stress.

7. The combination in a planer, of a reciprocating table, uprights at the sides of the 130

table, a cross rail carried by the uprights, a
5 tool head on the cross rail, a long bar secured
to the tool head and adapted to carry a cut-
ting tool at its lower end, and a supple-
mental transverse rail mounted on the up-
right independently of the cross rail and
engaging the bar near its upper end, the

supplemental rail being parallel to the cross
rail and thereby adapted to remain in en-
gagement with the bar for all positions 10
thereof.

In testimony whereof, I hereto affix my
signature.

WILLIAM J. HAGMAN.
